UNITED STATES PATENT OFFICE.

AUGUST J. FREY AND FRANK S. HYATT, OF BROOKLYN, NEW YORK, ASSIGNEES TO
BRASS GOODS M'FG CO., OF BROOKLYN, NEW YORK, A CORPORATION OF NEW
YORK.

TUBE-COMPRESSOR.

1,357,551.

Specification of Letters Patent.

Patented Nov. 2, 1920.

Application filed September 10, 1919. Serial No. 322,829.

To all whom it may concern:

Be it known that we, AUGUST J. FREY and FRANK S. HYATT, citizens of the United States, and residents of Brooklyn, in the 5 county of Kings and State of New York, have invented certain new and useful Improvements in Tube-Compressors, of which the following is a specification.

Our invention relates to clamping devices 10 designed to apply clamping pressure to a tube or similar object and which, as usually constructed, embody an actuating cam or member mounted in a pair of ears or brackets rising from one clamping member 15 and operating upon an upper or second clamping member arranged between the ears.

One form of device of this general character and made of sheet metal is described in 20 Letters Patent of A. J. Frey Nos. 1,217,433 and 1,297,456 and another form in which the parts are made of wire is described in patent of A. J. Frey No. 1,275,898.

Our invention, however, will be described 25 in connection with a form in which sheet metal is employed.

The objects of our invention are to insure 30 an effective clamping pressure upon the tube or other object introduced between the clamping members and also to simplify the construction and reduce the amount of metal required.

Other objects are to do away with elements or features of the previous constructions and so to facilitate the insertion of the tubing or other object between the clamping members. In the previous constructions the clamping jaws are carried respectively at the ends of a piece of sheet metal or wire 40 having a loop or bend through which the tube is inserted into position between the clamping jaws and in such previous constructions the tube or other object is clamped at one point only.

In the present invention the two clamping jaws or clamping members are independent of one another and the upper clamping member is supported loosely and guided in position between the cam supporting ears or uprights whereby it may accommodate itself readily to irregularities in shape or condition of the tube or other clamped object.

In our present invention furthermore, the 55 two clamping members are provided with

clamping jaws at opposite sides respectively of the point of operation of the operating cam or other device, thereby insuring an effective compression of the tubing and complete shutting off of the flow of liquid 60 through the same.

In the accompanying drawings:

Figure 1 is a side elevation of the compressor or compressing clamp embodying our invention and shows the parts in position for exerting the compressing action. 65

Fig. 2 is a side elevation showing the parts in position for insertion of the tube or other object between the clamps preparatory to the compressing action. 70

Fig. 3 is a detached plan view of the lower clamping member.

Fig. 4 is a detached plan view of the upper clamping member.

1 indicates the lower clamping member 75 from which rise the ears or brackets 2 as in previous constructions, forming a support for a pivoted cam 3 pivoted by its pintles 4 in said uprights and provided with the operating arms 5, 6 by which it may be caused 80 to engage or disengage the upper clamping member of the device. Said parts 3, 5, 6 are, as shown, made of a single piece of metal and provided with an intermediate strut or brace 7 as described in one of the 85 previous patents above mentioned.

The construction so far described is old in the art and will not be further referred to.

The lower clamping member 1 is provided 90 with a clamping jaw 8 with which co-operates a jaw 9 upon an upper clamping member 10. In previous constructions the member 10 forms one arm or end of a single strip of sheet metal, the other end of which terminates in the member 1, and is thereby 95 supported in proper position to hold jaws 9, 8 in relative position. The loop of the piece of metal or wire in case wire is employed, is usually perforated to allow insertion of the tube between the clamping members. 100

In our present invention the metal comprising the loop portion is entirely dispensed with and the upper clamping member 10 is loosely supported and guided in position over the lower member 1 in any suitable 105 way, as for instance by providing it with slits indicated at 11, through which the ears or brackets 2 pass so as to hold said loosely mounted member 10 against longitudinal as well as lateral displacement. Said member 110

10 being engaged by the cam 9 when the latter is operated, will compress the tube or other object in obvious manner, but owing to the loose mounting of the member 10 the 5 latter can accommodate itself to irregularities in the shape, size or condition of the tube and thereby operate with a more effective clamping pressure under varied conditions of use.

10 In addition to loosely mounting the member 10 as described, we provide the same with a clamping jaw 9' arranged so that jaws 9 and 9' will be at opposite sides respectively of the point of application of the pressure by the cam or other operating member to said member 10. The lower member 15 is likewise provided with another clamping jaw 8' which coöperates with jaw 9'. As will be seen, the member 10 being loosely mounted, the pressure on the two pairs of jaws will be equalized and pressure will be effectively applied at two points in the tubing, thereby insuring a complete closure of the same and stoppage of the flow. The rear 20 end of the member 10 is extended as indicated at 12 to form a stop for the arm 6 of the operating cam when the same is depressed to apply clamping pressure.

As will be seen, the difficulty encountered 30 in previous constructions owing to the necessity of threading the tube through an eye or opening at the rear of the device is avoided in our construction and it is only necessary to pass the end of the tube into 35 the space between the jaws 8', 9', the conformation of which is such that they assist in guiding the tube into and through the space between the clamping members 1, 10.

What we claim as our invention is:—

40 1. In a compression clamp of the character described, the combination of a lower clamping member having upright integral brackets rising from opposite sides thereof, a jaw operating cam having transversely 45 extending pintles engaged with said uprights and an upper clamping member loosely mounted and guided on said uprights and held thereby against longitudinal displacement.

50 2. In a compression clamp of the character described, the combination with a lower clamping member having ears or uprights integral therewith, a cam having pintles engaged with said uprights and an upper 55 clamping member loosely supported and guided on said uprights against lateral and longitudinal displacement.

3. In a compression clamp of the character described, an upper clamping member provided with two clamping jaws arranged respectively at opposite sides of the point of application of the operating pressure, and adapted to engage the object at two distinct points.

4. In a compression clamp of the character described, an upper clamping member loosely mounted and guided against lateral and longitudinal displacement and provided with two distinct clamping jaws arranged respectively at opposite sides of the point of application of the clamping pressure, and combined with a lower clamping member having a pair of distinct jaws coöperating respectively with the jaws on the upper member and provided also with guides integral with it for said upper member.

5. In a compression clamp of the character described, a lower clamping member provided with ears or brackets, and with clamping jaws at opposite sides respectively of said ears or brackets and an upper clamping member having coöperating jaws arranged respectively at opposite sides of the point of application of the clamping pressure and adapted as described to equalize the pressure on the jaws when subjected to the action of the compressing member.

6. In a compression clamp of the character described, having an operating cam and actuating arm therefor, a loosely mounted upper clamping member supported and guided independently of the lower member and provided with a rearwardly extending arm adapted to form a stop for the cam actuating arm.

7. In a compression clamp of the character described having a compressing cam and actuating arm for said cam, the combination of a lower member having cam supporting ears or brackets and clamping jaws at opposite sides respectively of said brackets and an upper clamping member loosely supported and guided upon said brackets and provided with a pair of coöperating jaws and with an arm adapted to form a stop for the cam actuating arm.

Signed at Brooklyn, in the county of Kings and State of New York this 30th day of August, A. D. 1919.

AUGUST J. FREY.
FRANK S. HYATT.
